UNITED STATES PATENT OFFICE

SAMUEL H. PARSON, OF BROOKLYN, NEW YORK

SMOKER'S ARTICLE

Application filed March 30, 1927. Serial No. 179,410.

This invention relates to smokers' articles, such as pipes, cigar-holders and the like, and more particularly, to arrangements in such articles for cooling and purifying the smoke produced by burning tobacco, prior to the inhalation of said smoke by the smoker. In tobacco pipes, for example, of conventional construction, the smoke of burning tobacco is usually delivered to the smoker at a relatively high temperature and with its full content of undesirable and injurious substances, such as nicotine, etc. One of the features of this invention is the provision of means in tobacco pipes and in other smokers' articles, for causing the smoke to traverse a somewhat longer passage than in usual practice on its way from the source to the smoker's mouth, for substantially cooling the smoke while traversing this passage, and for purifying the smoke by the substantial elimination of the injurious elements contained therein, which elements, when inhaled, may produce deleterious effects upon the smoker's physical and mental condition. One of the novel features of this invention is attained by providing in a particular tobacco pipe taken for illustrative purposes, a reservoir or chamber adjacent to the smoke passage or passages, conveying the smoke from the pipe bowl to the smoker's mouth, in which reservoir there may be confined a cooling medium, such as water, so that as the smoke produced in the pipe bowl traverses the smoke passage or passages, it will continually give off its heat to the cooling medium and reach the mouth of the smoker at a substantially lower temperature, in a cool condition, and pleasant and comfortable for inhalation. For the sake of convenience, water will be referred to hereinafter illustrative of any suitable cooling medium, although it is to be distinctly understood that any other cooling medium, preferably of liquid character, may be equally well employed instead of water without departing from the spirit and scope of this invention.

In this invention, at the same time that the smoke is being cooled during its passage from the pipe bowl to the mouth of the smoker, the smoke becomes substantially

purified by virtue of the fact that the injurious substances, suspended in the smoke and carried thereby, are separated from the smoke, these substances being deposited on some form of disc, for example, interposed in the path of the smoke. The disc may be adapted to act as a baffle, and as the smoke passes from the pipe bowl to the smoker's mouth, it may impinge upon the disc, the injurious substances contained in the smoke being thereby condensed and deposited on said disc. Accordingly, these injurious substances are thereby prevented from entering the smoker's mouth along with the smoke. The deposits of nicotine, etc., accumulating on the disc which is acting as a baffle, flow downwardly and may be removed in the periodical cleaning of the pipe. Thus, it becomes apparent that at the same time that the smoke is being cooled by the water in a reservoir, the injurious substances, such as nicotine and the like, are being deposited as a sediment, the purification of the smoke being accomplished by the presence of a disc which is acting as a baffle.

The action of the disc as a baffle may be considered to be automatic, the disc being so shaped that the smoke passage or passages remain open at all times for the transmission of smoke. As has already been stated, the disc is interposed in the path of the smoke, and as the smoke produces a suction in the smoke passage or passages in order to draw in some smoke, the disc, which is of a material of very light weight, is drawn toward the mouth of the smoker, remaining fixed in position as long as the suction continues. When the smoker stops drawing in smoke, the baffle may, if desired, be arranged, to move a short distance away from its former position. When a suction is again produced by the smoker, the disc is again drawn toward the smoker, and so it continues. The backward and forward movement of the disc, during smoking, is desirable because it causes the matter accumulating on the disc to merge into drops and then move downwardly out of the normal path of the smoke.

While this invention will be pointed out with particularity in the appended claim, the

invention itself, both as to its further objects and features, will be better understood from the detailed description hereinafter following, when read in connection with the accompanying drawing, in which Figure 1 represents one embodiment of the invention shown herein merely for the purpose of illustration, Fig. 2 shows a view of one of the elements of the illustrated pipe of Fig. 1, and Fig. 3 shows a perspective of another of the elements of the illustrated pipe of Fig. 1.

In Fig. 1 of the drawing, reference characters 2 and 4 designate the pipe bowl and shank respectively, these being of any shapes well known in the art. The shank has a water reservoir or chamber 6 formed therein, permanently closed at the end near the pipe-bowl 2 and closed at the other end by means of a threaded sealing member 8 and the enlarged end of the pipe-stem 10, as will be described more fully hereinafter. A cylindrical rod 12, preferably threaded at one end 14 and diminished in diameter at the other end 16, extends from the pipe-bowl 2 to a chamber 18. In the rod 12 there is a bore or smoke passage 20 running substantially parallel to the water-chamber 6. In the embodiment of this invention shown herein for illustrative purposes, a single smoke passage 20 is shown extending from the pipe-bowl 2 to the chamber 18. This smoke passage is preferably centrally disposed within shank 4, the water jacket or chamber 6 surrounding the smoke passage 20. The rod 12, which separates the smoke passage 20 from the water jacket or chamber 6, is of relatively small diameter and is made preferably of a metallic substance, such as aluminum, in order to permit a higher rate of heat transfer. In other words, the rod 12 is made preferably of a substance which will freely conduct heat contained in the smoke traversing the smoke passage 20 to the water-chamber 6, so that the water contained therein may thus absorb the heat transmitted, the temperature gradient of the smoke therefore decreasing considerably throughout the path of the passage 20.

The pipe-bowl 2 receives tobacco which may be burned therein. The portion of the pipe between the pipe-bowl 2 and the water-chamber 6 is shown threaded so as to receive the threaded terminal 14 of the rod 12. Yet it will be understood that the rod 12 may, in practice, be fixed in a position relative to the bowl 2 in numerous other ways well known to those skilled in the art.

The pipe-stem or mouthpiece 10 is enlarged at one end 22 and provided with internal and external screw threads. The external screw threads are employed to connect the pipe-stem 10 to the internally threaded open end of the shank 4. The other end of the stem 10 is provided with a tip 24 adapted to be received and held in the mouth of the

smoker. The stem 10 also has a central bore or smoke passage 26 extending from chamber 18 to tip 24. The smoke passage 26 may, if desired, be concentric with smoke passage 20.

A disc or baffle 28 is interposed in the path between smoke passage 20 and smoke passage 26. This disc or baffle is loosely disposed in the chamber 18, free to move backwardly or forwardly within chamber 18. Baffle 28 moves backwardly when a suction is established within smoke passage 26 and forwardly when the latter suction is released.

The threaded sealing member 8 is provided to close the water-chamber 6 in order to prevent water contained therein from leaking into the chamber 18. The threaded sealing member 8 is preferably cylindrical, threaded externally in order to be engageable with the internally threaded portion of the pipe-stem 10. The threaded sealing member 8 is hollow at the center, this hollow portion being also cylindrical and of sufficient diameter so that it may be freely moved over the necked portion 16 of the rod 12. The threaded sealing member 8 is shown herein resting against the shoulder of rod 12. Yet, if necessary, a gasket of a material such as rubber, fibre, or the like, may be placed against the annular surface of the threaded sealing member 8 adjacent to the water-chamber 6 in order to more tightly seal the water-chamber against leakage.

When the smoker takes a puff on his pipe, the smoke moves from bowl 2, through the smoke passage 20 within the rod 12, thence through the chamber 18, impinging upon the disc or baffle 28, thereby leaving any sediment or liquid substances contained in the smoke in chamber 18, thence around the disc or baffle 28, thence through smoke passage 26 and into the mouth of the smoker. It will be apparent that as the smoke traverses the smoke passage 20, the heat contained therein will be transmitted to the cooling medium confined within chamber 6.

The disc or baffle 28 may be grooved on both sides as shown. The groove near smoke passage 26 establishes a free path for smoke flowing from chamber 18 to smoke passage 26 when the baffle 28 is moved toward the smoker as is the case when suction is applied to the smoke passage 26. Yet due to the force of gravity, and due to the inclination of the walls of chamber 18, the disc or baffle 28 moves forwardly when the suction within smoke passage 26 is released. It is to be understood, however, that the disc or baffle 28, may, if desired, be grooved to mesh with a corresponding projecting element in chamber 18, or that projections may be provided within chamber 18 (as shown by the dotted lines therein) to control the lateral movement of baffle 28 within chamber 18, within the scope of this invention.

It will be further understood that the shank 4 may, if desired, be separate and distinct from pipe-bowl 2 and, furthermore, that shank 4 may be of a transparent material so that the smoker may observe the presence of the liquid medium within chamber 6 and its condition.

Fig. 2 shows a perspective of the disc or baffle 28 of Fig. 1, having the grooved portions on its front and rear sides. These grooved portions are shown in parallel relationship, yet they may be disposed at any angle with respect to each other within the scope of this invention.

Fig. 3 shows an embodiment of the threaded sealing member 8 of Fig. 1. It will be remembered that the sealing member 8 is threaded externally in order to be engageable with the internal threaded portion of the stem 10. Yet to facilitate the engagement of the threaded sealing member 8 with the stem 10, grooves 30 and 32 may be provided. These grooves permit a quicker adjustment of the threaded sealing member 8 with respect to the internal portion of the stem 10.

While the features of the present invention are shown with particular reference to smoker's articles, such as tobacco pipes, the features of this invention may also be incorporated in other smoker's articles, such as cigar holders, etc. Moreover, the particular shapes and dimensions of the smokers' articles may be varied as found desirable without departing from the spirit and scope of this invention.

While this invention has been shown and described in connection with one particular embodiment merely for the purpose of illustration, it is to be distinctly understood that the general principles of this invention may be applied to other and widely varied organizations without departing from the spirit of the invention or the scope of the appended claim.

What is claimed is:

In a tobacco pipe having a shank with an enlarged recess, the combination of a stem connected to the shank, said stem also having an enlarged recess, a tube located centrally within the shank of the pipe and extending from the bowl of the pipe to the stem, said tube being connected with the bowl and with the stem of the pipe in a watertight manner, and a disk located in the recess of the stem, said disk acting as a vibratory element during the smoking process.

In testimony whereof, I have signed my name to this specification this nineteenth day of March, 1927.
